WATER FAUCET

James R. Boyles, 9595 Gregory St., La Mesa, Calif.

Filed Mar. 9, 1964, Ser. No. 78,909

Term of patent 3½ years

(Cl. D91—3)

Fig. 1

Fig. 2

Fig. 3

Fig. 4

Fig. 5

FIGURE 1 is a perspective view of a water faucet, showing my new design;

FIGURE 2 is a rear elevational view thereof;

FIGURE 3 is a bottom plan view thereof;

FIGURE 4 is a side elevational view thereof, the other side being similar; and

FIGURE 5 is a side elevational view with the adjustable water outlet inverted.

The dominant features of my design reside in the portions shown in full lines.

I claim:

The ornamental design for a water faucet, as shown and described.
